UNITED STATES PATENT OFFICE.

LORING WOOD, OF GREENFIELD, MASSACHUSETTS.

WRENCH.

SPECIFICATION forming part of Letters Patent No. 268,844, dated November 28, 1882.

Application filed July 24, 1882. (Model.)

To all whom it may concern:

Be it known that I, LORING WOOD, of Greenfield, in the county of Franklin and State of Massachusetts, have invented a new and useful Improvement in Wrenches, of which the following is a full, clear, and exact description.

The object of my invention is to furnish a wrench especially applicable for removing nuts from axles, by which the nut can be taken off and replaced without the necessity of handling it.

The invention consists in constructing and combining certain parts of an axle-nut wrench, as hereinafter described, and pointed out in the claims.

Reference is to be had to the accompanying drawings, forming part of this specification, in which similar letters of reference indicate corresponding parts in both the figures.

Figure 1 is a side view, partially sectional, of my improved wrench. Fig. 2 is a plan view of the same.

The wrench, as shown, is an ordinary wagon or carriage wrench formed with a socket portion, A, for the nut and handle portion B. The handle B is grooved upon one side from the socket A to the outer end to receive the rod C, that is bent to the form of the handle, and projects at one end into the socket A, through an aperture in the side thereof. The outer end of this rod is bent at right angles and extends through a slot, a, in the handle, so as to receive a knob, b, by which the rod can be moved endwise. Upon the rod C is a spiral spring, d, which is fitted to retain the rod with its end projecting into the socket A.

This projecting end is beveled or otherwise shaped to take a notch that is to be cut in the corner of the nut.

In using the wrench it is to be applied to the nut as usual, the rod C being at the same time drawn back by means of its knob b, and after the wrench is in place the rod is to be allowed to spring forward, so that its end shall take the notch in the nut. The nut can then be removed, as usual, by turning the wrench, and the nut will be prevented from falling out of the wrench by the gripping-rod C, so that the nut can be again replaced, and the necessity of handling the nut is entirely avoided. The knob b forms a crank-handle upon the wrench for assisting the unscrewing and screwing up of the nut.

By this device nuts can be removed from carriage or wagon axles without soiling the hands, and much more conveniently than it can be done with the ordinary wrench. The notch in the nut is not essential, as the wrench will retain the nut without a notch.

Having thus described my invention, I claim as new and desire to secure by Letters Patent—

The combination, with the socket A, having a rear hole, and the slotted handle B, having a longitudinal groove, of the spring-actuated rod C, passing with one end into the socket, movable in the handle-groove, and bent up at the outer end to receive a knob, b, as and for the purpose specified.

LORING WOOD.
